UNITED STATES PATENT OFFICE.

KEITH H. ROUSE, OF SAN FRANCISCO, CALIFORNIA.

TIE-FORM.

1,134,910.

Specification of Letters Patent.

Patented Apr. 6, 1915.

Application filed August 27, 1912. Serial No. 717,357.

To all whom it may concern:

Be it known that I, KEITH H. ROUSE, a subject of the King of Great Britain, residing at San Francisco, in the county of San Francisco and State of California, have invented new and useful Improvements in Tie-Forms, of which the following is a specification.

The general object of this invention is the provision of a neck tie form which is so constructed as to enable a person to easily and neatly secure a tie thereto, and to this end the invention consists in providing a single length of wire bent into novel form 15 for the reception of said tie.

In carrying out the object of the invention generally stated above, it will be understood, of course, that the essential features thereof are susceptible to changes in 20 details and structural arrangements, preferred and practical embodiments being shown in the accompanying drawing, wherein:

Figure 1 is a front elevation of a preferred form of the invention. Fig. 2 is a similar view showing a tie applied thereto, a collar being shown in dotted lines. Fig. 3 is a vertical transverse sectional view through a portion of the form. Fig. 4 is an 30 edge elevation of the form. Fig. 5 is a front elevation of a slightly modified form.

Referring more particularly to the accompanying drawing in which like reference characters designate similar parts, it will be seen that the invention comprises a single length, of wire, generally indicated by *a*, said wire being made of any suitable material and bent medially the ends thereof to provide a loop 5 which is adapted to engage 35 a collar button in order to retain the form in engagement with the collar button and thereby secure the neck tie in an adjusted position. The wire is then crossed as indicated at 6 and the ends thereof are 40 passed through a cylindrical tube 7, the ends of said tube being adapted to engage the bent portions 8 of the wire *a* whereby to retain the neck tie form in its original shape. After passing through the tube 7, the free 45 ends of the wire *a* are bent so as to diverge at an angle from said tube and are also curved rearwardly to form arcuate collar engaging arms 9. The free extremities of the arms 9 are bent upon themselves as in-

dicated at 10 so as to prevent tearing or 55 otherwise marring the material from which the collar is made.

It will be particularly noted from Figs. 3 and 4 of the drawings that the sections of the wire passing through the tube 7 are in 60 offset relation and that said tube has a diameter materially greater than the diameter of the wire making up the form. By reason of this arrangement it will be obvious that a certain movement of the arms 9 independent 65 of their resiliency is permitted through the play of the wire in the tube. This permits a yielding of the arms in their adjustment with respect to the collar without distorting or disturbing the device as a 70 whole.

In applying a neck tie to the form, the latter is first grasped at the loop 5 between the thumb and fore finger of either hand and after adjusting the tie to its proper 75 length the same is held in position by the thumb and is turned over the tube 7 and around one of the arcuate arms 9. The tie is then passed over the thumb and around the other arcuate arm 9 and the free extremity of the tie is then passed through the space formed by a portion of the tie engaged between the loop 5 and the portion passing over the thumb and said end is then drawn taut in order to make the tie 85 conform to the contour of the form.

In Fig. 5 of the drawing there is shown a slight modification in which the loop 5 is bent in a slightly different manner from that of the corresponding loop in the preferred 90 form in order that the form may be attached to different kinds of collar buttons.

From the foregoing description taken in connection with the accompanying drawing, it will be seen that the invention contemplates providing a neck tie form which is exceedingly simple in construction thus reducing the cost of manufacture of the same to a minimum and which is durable and effective in carrying out the purpose for 100 which it is designed.

What is claimed is:

In a device of the character described comprising a wire strand, said wire strand being shaped to provide two equal side stems, said 105 stems being crossed at one end, an integral inverted U-shaped loop projecting toward the point of intersection of said stems and.

2
formed integrally thereupon, each of said stems having a portion of its length forming an acute angle with said intersecting stems, said last mentioned portions arranged to intersect, a sleeve surrounding said last mentioned portions to hold them under tension therein, and oppositely arranged upwardly divergent and rearwardly curved terminals formed upon said stems and hav-

ing rounded offsets upon their extreme ends.

In testimony whereof I affix my signature in presence of two witnesses.

KEITH H. ROUSE.
